DUMPING RECEPTACLE

George O. Harm, Warren, Ohio, assignor to The Stevens Metal Products Company, Niles, Ohio, a corporation of Ohio

Application July 12, 1933, Serial No. 680,012

6 Claims. (Cl. 298—8)

My invention is an improvement in dumping receptacles and relates more particularly to that type of dumping receptacle which is used in connection with a tilting vehicle body for conveying and delivering batches of material. The present invention relates more particularly to such a receptacle which is adapted to retain its charge regardless of the position of the receptacle with respect to the vehicle body, until it

10 is desired to release the charge and discharge the same into the body or a compartment thereof as when the vehicle body is tilted. The invention further relates to dumping receptacles of this type which may be handled conveniently in charging it with materials, or discharging its contents without the aid of latches or other locking devices.

The invention is particularly well adapted for use in connection with a tilting truck body for 20 separately transporting or storing a mixture of fine and coarse aggregates, and the cement for a concrete batch, and for discharging the cement into or with the aggregates as they are discharged from the truck body.

25 It is one of the objects of my invention to so construct the receptacle and its mounting with respect to the vehicle body on which it is supported, that it will be unnecessary to employ latching devices or locks to retain the receptacle, when loaded, in an upright position on the vehicle body.

It is a further object of my invention to adequately protect materials such as cement, which may be carried by the receptacle, by preventing 35 access of moisture into the interior of the receptacle, and at the same time to eliminate interference or obstruction to the operation of the receptacle in dumping the material, or to interfere with the loading of the receptacle.

40 A still further object of the invention resides in simplicity of construction and operation of the device and thereby materially reduce the cost of manufacturing of such articles without sacrificing strength or durability.

45 Another object of my invention is to provide a simple mounting for receptacles of the above mentioned character whereby the said receptacles may be quickly and removably mounted and supported upon the upper edges of the vehicle body sides, thus eliminating the use of cumbersome mounts or standards, and permitting at all times proper positioning of the receptacle on its support.

50 A still further object of my invention is to provide a dumping receptacle which may be mounted

on a vehicle body and which has freedom of movement between loading and discharging limits.

Other objects and advantages of my invention will become more apparent as the following description of one embodiment thereof progresses, reference being made to the accompanying drawing in which like reference characters are employed to designate like parts throughout the same.

In the drawing:

Figure 1 is a side elevation of an embodiment of my invention shown applied in use on a tilting truck body. In this view the truck body is shown in solid lines in its normal horizontal position, the receptacles being shown in full lines 15 in an upright position. In this same view the tilted position of the truck body is indicated in broken lines, and one of the receptacles in one of the compartments of the truck body is shown in its discharging position with the cover free 20 from the open end of the receptacle.

Figure 2 is a fragmentary side elevation of an apparatus embodying my invention and shows the dumping receptacle in its two limits of movement, that is, in charging position, and, in broken 25 lines, in discharging position, and,

Figure 3 is a fragmentary front view of one of the receptacles and illustrates one manner of mounting the same on the side walls of the vehicle body.

Referring now more particularly to the figures, I will proceed to describe the construction and operation of the embodiment of my invention shown in these figures, although it will be understood that the embodiment shown is merely 35 by way of illustration and I do not limit the invention to the details shown. The truck body 1 may be pivotally mounted as at 2 so that the body may be tilted to a position like that shown in Figure 1 for discharging materials through the 40 end gate 3 as indicated at 4. The truck body is preferably divided into compartments by means of one or more batch gates 5 which are pivotally mounted as at 6 to swing rearwardly when released. In dumping the contents of the truck 45 body and the receptacles, the rear compartment is discharged first as indicated in the drawing, whereupon the respective forward compartments may be likewise discharged, the contents passing through the open end gate 3.

In further carrying out my invention I provide receptacles 7 which may be mounted in each of the compartments of the truck body. These receptacles are preferably made of sheet metal and are provided with an open top end for re- 50 55

ceiving and discharging materials such as cement. The open end of each receptacle is provided with a cover or lid 8 which is adapted to be operated at the will of the user. This phase 5 of my invention will be described more fully hereinafter.

The dumping receptacles 7 are each provided with suitable trunnions 9 which extend outwardly from opposite sides of the receptacle for supporting the same in a suitable bearing member carried by the side walls of the truck body. These trunnions may extend through the receptacle or may be welded to the sides thereof and define the turning axis of the receptacles. The turning axis 15 is preferably located below the center of gravity of the receptacle, when loaded, and preferably in a plane which may be defined as "off-set" rearwardly from the vertical central axis of the receptacle. The receptacle will normally assume 20 a substantially upright position as shown in full lines in Figure 2, the receptacles being normally tilted but slightly toward the forward end of the truck body. The movement of the receptacle in this direction may be limited by means of segment-like stops 10 which are carried near the outer ends of the trunnions 9 and which are bolted or otherwise secured thereto. The segments 10 are so designed that when the receptacle is in the full line or upright loading position 25 as shown in Figure 2, the edge 11 of each segment will rest upon a projection 12 of the bearing plate 13, while when the receptacle is rotated to discharging position, through an arc of less than 135°, as indicated by the broken lines 30 the opposite edge 14 of the segment will rest upon a projection 15 on the opposite end of the bearing plate 13, thus determining the limit of movement of the receptacle in both directions but providing freedom of movement thereof between 35 these limits.

I have provided very simple and inexpensive bearing and supporting members 16 for the trunnions of the receptacles whereby the receptacles may be tiltably mounted on the side walls of the 45 vehicle body. According to my invention one simple form of such a bearing or support may consist of a plate 16 which is formed with an upstanding portion 17 apertured to receive the end 18 of the trunnion. These plates are provided with depending portions 19 which abut the inner side walls of the vehicle body and are bolted thereto as at 20. In order that the receptacles may be properly spaced from the side walls of the vehicle body the trunnions are provided 50 with a series of spaced openings 21 for receiving a bolt 22. The segment 10 is provided with a sleeve-like portion 23 which is also apertured to receive the bolt 22. It will be seen therefore that the segment may be secured to turn with the trunnion in any one of a plurality of adjusted positions lengthwise of the trunnion, depending upon the width of the truck body, while at the same time the segment may be readily removed after the bearing member has been removed. It will also be noted that the segment is 55 located between the plate 17 and the receptacle. In this manner I have provided against side sway of the receptacle.

My invention also contemplates the provision 70 of a cover for the tilting receptacles which may be readily operated by the operator to permit charging or discharging of the receptacle. The invention also provides for a cover which may be clamped securely in place to cover the open 75 end of the receptacle so as to prevent the pas-

sage of moisture into the receptacle or to prevent either part or full discharge of the contents when such discharge is not desired.

These covers 8 are preferably made of sheet metal and are provided with side members 24, 5 and are pivotally mounted close to the open end of the receptacle as at 25. Suitable handles 26 are keyed to the shaft 25 for operating these covers. The forward end of each side member of the cover is provided with a turned end 27 10 which is adapted to engage a cross rod 28 carried along one of the edges of the open end of the receptacle. Additional straps with ends similarly turned are spaced along the cover for further reinforcement. While the cover is primarily 15 pivotally mounted upon the receptacle it is also capable of a sliding movement transversely of the shortest dimension of the receptacle opened end. This sliding movement of the cover is accomplished by means of one or more cams 29 20 which are keyed to the shaft 25 and rotate therewith, the cams operating in bearings 30 mounted on an inclined wall 31 of the receptacle. These bearings 30 are located in such a position on the receptacle that when the shaft 25 has reached 25 substantially the limit of movement toward the forward part of the truck body the turned ends 27 of the cover have tightly engaged the cross rod 28. Further movement of the handle pulls the forward portion of the cover down against 30 the edges of the receptacle to provide a tight closure, due to the cam action tending to carry the shaft 25 downward toward the receptacle body.

Handles 32 may be provided on the cover to 35 permit lifting the same when the handle 26 is rearward and while the receptacle is in an upright position.

It will be seen that by my invention I have provided a very simple, durable and inexpensive 40 means for charging, conveying and discharging a quantity of material into a vehicle body whereby the material is to be mixed with other materials and is discharged with other materials supported within the body when said body is tilted. 45 Furthermore by my invention I have eliminated the use of cumbersome supporting means for the tilting receptacle and have also eliminated the necessity for latching or locking mechanism to maintain the receptacle in a desired position. 50

Various changes may be made in the details 55 of construction and arrangement of parts without departing from the spirit of my invention or the scope of the appended claims.

I claim:

1. A vehicle charging receptacle tiltably mounted on the vehicle and having a charging and discharging opening, a cover operating to close the opening, and means for operating said cover including bearings carried by the receptacle, a 60 rotatable shaft passing through said bearings, cams keyed to the shaft and operating in said bearings, said cover being freely rotatable on said shaft and movable thereby in a sliding motion across the opening when the shaft is rotated.

2. In a charging receptacle tiltably mounted upon a tiltable vehicle body and open at but one end to receive and discharge material, said receptacle being freely tiltable on the body on one 70 side of a vertical plane passing through the turning axis of the receptacle, a cover to close the open end of the receptacle, and means for hingedly supporting the cover on the receptacle, said means including a shaft and means operable 75

through said shaft to latch or unlatch the cover from the receptacle.

3. In a charging receptacle tiltably mounted upon a tilttable vehicle body and open at but one end to receive and discharge material, a member movable with the receptacle, stops on the vehicle body and located in the path of movement of said member to limit the free movement of the receptacle to an arc of less than 135°, a cover to close the open end of the receptacle, and means for hingedly supporting the cover, said means including a shaft, and means operable through the hinge to latch or unlatch the cover from the receptacle.
5. In a charging receptacle tiltably mounted upon a tilttable vehicle body and open at but one end to receive and discharge material, said member movable with the receptacle, stops on the vehicle body and located in the path of movement of said member to limit the free movement of the receptacle to an arc of less than 135°, a cover to close the open end of the receptacle, and means for hingedly supporting the cover, said means including a shaft, and means operable through the hinge to latch or unlatch the cover from the receptacle.
10. 4. In a charging receptacle tiltably mounted upon a tilttable vehicle body and having but one open end, said receptacle being freely tilttable on the body thru an arc of less than 135°, a cover to close the open end of the receptacle, and an eccentrically revolvable shaft for hinging said cover to the receptacle, said cover having portions to securely engage an edge of the open end of the receptacle when the shaft is turned.
15. 5. In a tilttable vehicle body a tilting receptacle having an open end, a support for the receptacle, a cover for the open end of the receptacle, bearings carried by the receptacle, an eccentric hinge pin operating in said bearings and said cover, said cover having a portion to securely engage an edge of the open end of the receptacle, and a crank for turning said hinge pin to effect a latching or unlatching of the said edge of the cover and the receptacle.

6. In a charging receptacle tiltably mounted upon a tilttable vehicle body and open at but one end to receive and discharge material, said receptacle being freely tilttable on the body on one side of a vertical plane passing through the turning axis of the receptacle but within an arc of less than 135°, a cover to close the open end of the receptacle, and means for hingedly supporting the cover on the receptacle, said means including a shaft and means operable through said shaft to latch or unlatch the cover from the receptacle.
